VOLUME AND PRESSURE-CONTROLLED
ROTARY PUMPStanley D. Ross, Vancouver, British Columbia,
Canada

Application May 16, 1934, Serial No. 726,007

2 Claims. (Cl. 103—120)

This invention relates to improvements in rotary pumps and compressors and the improvements are directed to providing positive and force feed lubrication to the bearings thereof, and to means for controlling and adjusting the pressure and volume of the pump when in operation.

A particular object of my invention is to provide a pump or compressor suitable for use in carrying out my process of carburetion as set out in a co-pending application recently filed.

A further object of my invention is to provide a pump or compressor having improved lubricating means for the main bearings as being attached directly to an electric motor. Such devices usually run at high speed and require positive lubricating means at these points to prevent running hot.

A still further object of my invention is to provide simple and positive pressure adjusting means whereby the discharge of the pump or compressor may be regulated as to pressure.

Still another object of my invention is to provide volume regulating means whereby the output of the pump or compressor is subject to adjustment.

Another object of my invention is to provide means whereby the suction or vacuum of the pump or compressor may be regulated to meet varying conditions.

With these and other objects in view I have invented the improvements that are the subject of this application and which are further illustrated in the accompanying drawing forming part of this application, in which:

Figure 1 is a side elevation of a rotary compressor showing discharge and suction connections and an adjusting screw in the end cover.

Figure 2 is a sectional elevation taken on line 2—2 of Figure 1 and shows a balanced rotor in position with movable vane extended out of its housing by the compression spring. The opening of the suction port is shown in right-hand corner, and the opening for the regulating screw in left-hand corner.

Figure 3 is a sectional view taken on the line 3—3 of Figure 2 and shows how the regulating screw closes the end of the discharge duct which is indicated in dotted lines in Figure 2.

Figure 4 is an outside plan view of the end cover plate fitting the suction side of the compressor and shows the suction port therethrough and the regulating screw aperture.

Figure 5 is an end elevation of cover plate shown in Figure 4.

Figure 6 is a detail and sectional view of part of

cover plate taken on line 6—6 of Figure 5 to show the position of the transfer duct formed in the cover plate to form a bye-pass from the discharge side to suction side of compressor.

Figure 7 is another detail and sectional view of a part of the cover plate taken on line 7—7 of Figure 4 and shows the recess formed on inner side of cover plate at the end of the regulating screw aperture and shows the end of transfer duct breaking into the side of the recess.

Figure 8 is another detail and sectional view of a part of the cover plate taken on the line 8—8 of Figure 4 and shows how the transfer duct or bye-pass is formed in the cover plate by drilling from the edge of the recess shown in Figure 7 and connecting with a hole drilled through from the edge of the suction port on the inner side of cover.

Figure 9 is a sectional elevation of the cover plate taken on line 9—9 of Figure 4 and diagrammatically illustrates the position of the lubricating ports drilled into cover to serve the main end bearing.

In the drawing like numerals of reference indicate like parts in all the figures, and the numeral 1 indicates a rotary compressor body having the 25 feet 2 for support and a pair of end cover plates 3 and 4, the plate 3 covering the discharge side of the compressor and the plate 4 the suction side.

Bosses 5 are cast on each cover plate and comprise the main bearings to the compressor.

A concentric aperture 6 is formed right through the main body 1 which is closed by the cover plates 3 and 4 when the compressor is assembled. An eccentric and balanced rotor 7 is mounted in the aperture 6 carried in the main bearings 5 by the 35 shaft 8 of the rotor. One end of the shaft 8 projects through the end cover plate 4 to provide a connection or drive, while the other end of the shaft is a stub bearing housed in the boss 5 on the cover plate 3.

Formed in axial alignment with the shaft 8 is a slotted aperture in the bottom of the interior compressor body forming a housing 9 for the movable vane 10 which is held in contact with the eccentric rotor 7 by the helical compression spring 11 carried in the spring housing 12 secured in the bottom of the main body 1.

Spaced apart on each side of the vane housing 9 are the discharge port 13 and suction port 14 50 registering with the port apertures in the end covers 3 and 4 when assembled.

At the extreme inner end of the horizontal portion of the discharge port 13 is an extension port 15 drilled right through the main body 1 and the 55

outer end registers with the needle valve aperture 16 formed in the end cover 4.

In the end cover 4 is mounted the needle valve 17 registering with and controlling the opening 5 of the port 15. A lock nut 18 is provided for securing the setting of the needle valve 17.

Upon the inner face of the cover 4 is formed a recess 19 at the end of the needle valve aperture 16 and drilled in from the edge of the recess 10 is the bye-pass passage 20 (see Figure 8) communicating with the suction port opening 14 in the cover plate 4.

The bye-pass 20 has the important function of controlling the volume and pressure discharge 15 of the compressor and pump and also the suction by manipulation of the needle valve 17, opening, closing and adjusting the extension port 15, as for instance, by opening the port 15 through the backing off of the needle valve 17, the pressure 20 set up on the discharge side of the compressor is lowered by reason of the opening of the bye-pass which permits the escape of the fluid in the compressor to the suction side, thereby lowering both the volume and pressure being discharged 25 through the discharge port 13.

Opening of the port 15 also lowers the suction 30 of the compressor and pump through permitting of internal circulation within the compressor from the discharge to the suction side which effects the external suction by lowering the vacuum within the compressor.

In the boss bearings 5 are provided forced lubricating means comprising drilled ducts 22 and 35 23 communicating with the ends of the bearings 5. A concentric recess 24 is formed adjacent the outer end of the bearing communicating with the duct 23, the opposite end of which is in open communication with the suction side of the compressor or pump, while the other duct 22 is in 40 open communication with the pressure or discharge side and leads to another concentric recess 24a spaced from and similar to the recess 24. This arrangement permits of a circulation being set up in the duct 22 to the inner end of 45 the bearing 5 whence the oil travels to the outer end towards the recess 24 where it is stopped from further progress through the suction set up in the recess 24 being in communication with the suction duct 23 through which the oil is 50 returned to the compressor.

Of course, it is assumed that the compressor and pump is handling some form of liquid hydrocarbons for this form of lubrication to be effective.

Having now described my invention what I 55 claim and desire to be protected in by Letters Patent, is.

1. In a rotary compressor and pump, a compressor body having a transverse passage through 60 the same from side to side constituting a cylindrical working chamber, a pair of end cover plates

secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 25

2. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 30

3. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 35

4. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 40

5. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 45

6. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 50

7. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 55

8. In a rotary compressor and pump, a compressor body having a transverse passage through the same from side to side constituting a cylindrical working chamber, a pair of end cover plates secured to the sides of said body as closures for said passage, said cover plates having shaft bearings, a shaft located in said bearings and passing through said working chamber, a rotor eccentrically mounted on said shaft within said working chamber, a relatively stationarily located reciprocating vane carried by said body and in cooperation with said rotor dividing said working chamber into a suction side and a discharge side, said body having a suction port and a discharge port, each of said ports including a portion parallel to the axis of the body with which portions the covers have communicating openings for connection of fluid intake and outlet pipe lines respectively, each of said suction and discharge ports also including radial portions communicating with said working chamber, the discharge port extending entirely through said body and terminating opposite the outlet end thereof in a reduced end, a needle valve carried by one of said cover plates to cooperate with said reduced end, said last named cover plate having a bye-pass duct from said needle valved end of said discharge port to said suction port for purposes described. 60
